UNITED STATES PATENT OFFICE.

FRANK X. MUDD, OF CHICAGO, ILLINOIS.

LOOSE-LEAF BINDER.

SPECIFICATION forming part of Letters Patent No. 689,110, dated December 17, 1901.

Application filed June 25, 1901. Serial No. 65,919. (No model.)

To all whom it may concern:

Be it known that I, FRANK X. MUDD, a citizen of the United States, residing at Chicago, in the county of Cook and State of Illinois, 5 have invented a new and useful Improvement in Loose-Leaf Binders, of which the following is a specification.

My invention relates particularly to automatically-locking adjustable binders; and my 10 primary object is to provide a practical locking device which will operate to keep the binder-sections firmly connected regardless of the degree of separation thereof and of the state of fullness of the binder.

15 My invention is illustrated in its preferred form in the accompanying drawings, in which—

Figure 1 is an inner perspective view of the lower back section; Fig. 2, a similar view 20 of the upper back section; Figs. 3 and 4, enlarged broken longitudinal sections of the binder, taken as indicated at the corresponding lines of Fig. 1; Fig. 5, a broken section taken as indicated at line 5 of Fig. 4; Figs. 6 25 and 7, sections taken as indicated at the corresponding lines of Fig. 4, and Fig. 8 a key for unlocking the locking device.

A represents an upper cover-section; B, a lower cover-section. Preferably there are employed 30 an upper clamping-bar A' in connection with an angle-iron A² and a lower clamping-bar B' in connection with an angle-iron B². The iron A² has a forwardly-turned flange a, to which the bar A' is attached, a downwardly-turned flange a', which forms a portion 35 of the rear wall of the binder, and end flanges a², formed with guide-grooves a³. The angle-iron B² has a forwardly-turned flange b, to which the bar B' is attached, an 40 upwardly-turned flange b', which forms a portion of the rear wall of the binder, and end flanges b², which engage the grooves a³. The two angle-irons telescope with each other, as appears clearly from Figs. 3 and 4. Projecting 45 downwardly from the flange a are tubular studs or posts a⁴, which telescope with smaller tubular posts b⁴, which project upwardly from the flange b. Confined within said hollow posts are coil-springs b⁵, which 50 tend to keep the cover-sections separated.

Depending from the flange a of the upper angle-iron and connected with the flange a'

thereof is a sheath C, comprising a curved or half-cylindrical front portion c and divergent sides c'. Within said sheath is a stud C', 55 journaled in the flange a of the upper angle-iron, said stud being provided at its upper end with a rigidly-attached key-receiving head c², which is countersunk in the upper surface of the flange a and is provided with a 60 projection c³, which moves in a half-annular groove c⁴, with which the flange a is provided. As shown in Fig. 7, the stud C' has a curved surface c⁵, flanked by rearwardly-convergent surfaces c⁶, the latter surfaces being provided, 65 as shown in Fig. 5, each with a series of indentations, the indentations of one row being staggered with relation to the indentations of the other row. Said stud C' is further provided at its lower extremity, on one portion 70 of its cylindrical surface c⁵, with an indentation c⁷. The indentations have abrupt shoulders at their lower portions, as shown.

Projecting upwardly from the flange b of the lower angle-iron and connected with the 75 flange b' thereof is a sheath D, having a curved front wall d, flanked by rearwardly-divergent walls d'. Pivoted to the inner surfaces of the divergent walls d' are spring-held pawls d². The pawls d² are located in the 80 same horizontal plane at or near the upper end of the sheath D and engage the indentations on the divergent surfaces c⁶, the pawls alternating in effectively locking the upper clamping-bar against withdrawal. The 85 binder-sections are suitably covered with leather or cloth cemented in place, as shown. The key-receiving head c² of the stud C' is provided with perforations, as shown, for receiving the key. 90

The manner of use will be readily understood by those skilled in the art. The leaves to be bound are suitably perforated or notched at their binding-margins to receive the binding-posts and the central sheaths of the locking device. Any desired number of leaves are put in place and the upper cover-section pressed downwardly, whereupon the pawls d² serve to prevent retraction. Owing to the arrangement of the pawls and notches, one 95 of the pawls will always be in position to engage a notch, thereby preventing any looseness. When desired, the stud C' may be turned through the medium of a key till the 100

pawls d^2 engage the cylindrical surface c^5 of said stud, whereupon the upper binding-section can be lifted till the notch c^7 is engaged by one of the pawls. This prevents entire separation of the sections. When desired, however, the key may be again employed to disengage the notch c^7 from the pawl with which it chances to be in engagement, and thereupon the binder-sections may be entirely separated. The ends of the curved groove c^4 serve as stops for the projection c^3 . When the projection c^3 is at one end of said slot, the pawls d^2 will engage the notches on the surfaces c^6 , provided the upper cover-section is at the right height, and when the projection c^3 is at the other end of the slot c^4 the pawls are in position to engage the surfaces c^5 , one of the pawls being then in position to engage the notch c^7 when the same is encountered. Assuming the notch c^7 to be engaged by one of the pawls, the parts may be disengaged by returning the projection c^3 to its first position, whereupon the pawls will encounter the smooth surface above the rows of indentations on the surfaces c^6 .

As appears from Figs. 1, 3, and 4, the flanges a and b are reinforced or strengthened at their central portions to prevent flexure. This is accomplished either by making the flanges thicker at their central portions or by means of separate reinforcing-strips. The result is that the leaves are evenly compressed and the cover-sections do not bend.

By employing two rows of notches arranged as described the desired closeness of locking may be secured without making the notches too close together. The construction may be varied in detail, however, without departure from the feature of the double lock employed.

What I claim as new, and desire to secure by Letters Patent, is—

1. In a loose-leaf binder, the combination of two adjustably-connected clamping-bars, a sheath connected with one of said bars and provided with two pawls, and a rotatable stud connected with the other of said bars and provided over a portion of its surface with indentations with which said pawls engage, said pawls having such location with reference to the indentations as to serve alternately in effectively locking the parts together, substantially as and for the purpose described. 45

2. In a loose-leaf binder, the combination of two adjustably-connected clamping-bars, two pawls supported from one of said bars and having locking-surfaces at the same height, and a rotatable stud connected with the other of said bars and provided with two convergent surfaces bearing two rows of indentations, the indentations of one row being staggered with relation to the indentations of the other row, substantially as and for the purpose described. 55

3. In a loose-leaf binder, the combination of two adjustably-connected clamping-bars, a sheath projecting upwardly from one of said bars, said sheath having two rearwardly-divergent walls, pawls pivotally connected to said divergent walls within the upper end of said sheath, a sheath projecting downwardly from the other clamping-bar, and a rotatable stud within said sheath having two forwardly-divergent surfaces, each equipped with a row of indentations, the indentations of one row being staggered with relation to those of the other row, said sheaths having telescopic connection, substantially as described. 60 70 75

FRANK X. MUDD.
